Primary Examiner—Brian N. Vinson*Attorney, Agent, or Firm*—Harris, Tucker & Hardin, P.C.[57] **CLAIM**

The ornamental design for a bathtub toy holder, as shown and described.

DESCRIPTION

FIG. 1 is a front elevational view of a bathtub toy holder showing my new design;

FIG. 2 is a top plan view thereof;

FIG. 3 is a right side elevational view thereof; the left side being a mirror image of the right side;

FIG. 4 is a bottom plan view; and,

FIG. 5 is a rear elevational view thereof.
